UNITED STATES PATENT OFFICE.

CHARLES H. CAMPBELL, OF BROOKLINE, MASSACHUSETTS.

HINGE.

Application filed June 5, 1925. Serial No. 35,214.

The present invention relates to hinges, and is particularly intended and designed as a connection between the cover and body of a tin can, such as those used to contain crackers, or between a frame of sheet metal, adapted to be placed over a cracker carton, and a cover connected to such frame.

The main object of the invention is to provide a firm, strong and secure hinge anchor especially adapted to the uses above set forth; that is, to the purpose of connecting a relatively heavy cover to a structure made of light sheet metal.

More generally, the object and accomplishment of the invention are to connect a relatively heavy swinging member, by a hinge, to a supporting structure, which may be made of relatively light and flexible construction, in an especially secure and strong manner. I have accomplished this object by providing a hinge anchor which comprises a sheet metal strip wrapped about a wire or rod, which forms the hinge pindle and is a part of, or is connected to, the cover structure, and the ends of such sheet metal strip are passed through a slot in the base structure and there bent over and back to form lugs or flanges having a total width greater than that of the slot, whereby to prevent the hinge anchor from being pulled out from the base structure.

A further object is to enable such hinge anchor to be easily and economically assembled with the body structure and secured thereto, with a minimum of wasted time and effort on the part of the work people, and with a maximum of uniformity, accuracy and security in the formation and placement of the holding lugs of all the hinge anchors so assembled. This second object is accomplished by a mode of procedure or method in assembling the parts of the hinge, which also I claim as part of the invention.

In the drawings herewith furnished to illustrate the principles and characteristics of the invention,—

Fig. 1 is a perspective view showing a frame or open top, which is provided for use in retail grocer shops to be placed on cartons containing crackers and biscuits; to which frame is attached a hinged cover by means embodying the present invention;

Fig. 2 is a cross section on an enlarged scale, showing the construction of the hinge and its anchor in full detail;

Fig. 3 is a similar view showing essentially the same structure, but with the hinge anchor reversed in position;

Figs. 4 and 5 are sectional views showing the intermediate stages in the process of applying the hinge anchor to the pindle rod or wire of the cover and forming it preparatory to insertion of the frame;

Fig. 6 is a view showing the final step of securing the hinge anchor in the frame.

Like reference characters designate the same parts wherever they occur in all the figures.

The part, which in the brief description of Fig. 1, I have called a frame or top member, comprises four side walls *a* adapted to embrace the sides of a pasteboard carton, a top ledge *b* extending inward from each of the four walls and adapted to rest on the top of the carton, and a lip *c* at the inner edge of such ledge, said lip defining the opening through which access is had to the interior of the carton. In a broader sense, this frame represents and typifies any base structure to which a cover or other hinged member may be secured. It is made of so-called tin, of very thin gauge, being thereby flexible and of no great strength. It may be made in any fashion known to the tinsmith's art, and may be reinforced, as required, by wires around either or both outer edges of its walls, so as to have as much strength as is needed for the service it is to perform.

d represents the cover which is hinged at one edge to the base frame *a*. The cover itself embodies a frame, in which is mounted a glass pane *e*, which is preferably reinforced with a wire extending along each of its four edges *d'*, *d''*, *d'''*, *d''''*. The wire, or that part of the wire, extending along the edge *d''''* constitutes the hinge pin or pindle.

As the cover is relatively heavy and is formed to embrace and overlie the lip *c*, bounding the entrance to the body frame, while such body frame is of light and flexible construction, a strong and well secured hinge anchor is required. I have provided in the article here shown, three such hinge anchors, which are spaced at convenient intervals along the wire in the edge *d''''* of the cover, one being at the middle of such edge, and the other two being near the ends of the edge. The wire is shown at *f* in the sectional views. All the hinge anchors are alike, wherefore a description of one will

answer for all. Such anchor consists of a strip or thin plate *g* of tin, that is, the same sort of sheet metal used in making the body frame and cover, and permissibly of the same gauge also. Said strip *g* is bent near its middle on a curve of a radius slightly larger than the hinge wire *f*, and is placed over the wire, as shown in Fig. 4. Then one half of the strip is offset toward the other part, so as to completely surround the wire. Those parts of the strip which project from the wire, and are brought by such offsetting close together, form what, for the purpose of this description, I will call a tab. It is formed of two thicknesses or plies of the sheet metal. Such tab is passed through a slot *h* in the flange *b* of the base member, and then bent down close against the inner surface of the flange at one side of the slot, then doubled back in the opposite direction and carried across the slot, preferably out to the wall *a*. The tab, thus bent and doubled back and forth, makes lugs or flanges *i*, *j*, which underlie considerable areas of the ledge *b* on either side of the slot *h*, and are pressed close against the under side of the flange, thus holding the hinge eye, which is formed by the doubled middle part of the original strip *g*, closely and firmly against the base frame, and making it impossible for the hinge to be disconnected except by force great enough to tear and destroy the base frame. The strip *g*, which is thus formed and entered into the base frame and flange, provides what I have called the hinge anchor.

The bending and folding of the hinge anchor tab to form such lugs, particularly when a number of them are to be thus folded and set at once, is liable to involve much difficulty and uncertainty. It is necessary, as a matter of commercial practice, that when two, three or more such hinge anchors are applied to the same structure, the tabs of all should be folded and secured at one operation, on account of the saving in cost by so doing over the cost of folding them separately. But this requires that the cover, (the member which carries the hinge pintle,) and the base frame, both be so held that the tabs of all the anchors project through their respective slots in the part *b*, and that the projecting tabs be folded over by dies, or a die, in a press. When the tabs are straight in initial formation, it is exceedingly difficult, and practically impossible, so to hold them in the press that they will all extend in the same direction and all will be properly engaged by the die or dies, and all will be folded correctly; for the sheet metal in which the slots *h* are formed is so thin that the sides of the slots are unable to hold the tabs upright, while a slight tilting or cocking of the tab will prevent its being folded and pressed against the

surface of the base member in the manner required to form the lugs above described.

I have devised a method of folding the tabs which ensures their correct final formation and placement, and wholly avoids the tendency or liability toward wrong placement above described. This method is a part of the invention which I desire to protect herein. It comprises a preliminary bending of the tab of the hinge anchor, prior to placement in the base frame, in a manner such that the location of the folds is established, and bending of the tab to form flanges of the required length and disposed in the required positions is assured.

The preferred steps employed in carrying out this method are illustrated in Figs. 4 and 5. Preferably, the same dies which close the U-shaped strip around the hinge wire are also appropriately formed to put the bends in the tab of the resulting hinge anchor; and preferably, also, all of the hinge anchors applied to the same cover are so closed in and bent at once, but this latter detail is not essential. The complementary dies comprise a base member *k* and a punch member *l*. In the base member is a recess *m* to receive the hinge wire, a ridge *n* adjacent thereto, and a groove *o*, these ridges and grooves all running parallel to the hinge wire; and in the punch member is a groove *p* to receive the hinge wire, and a ridge *q* complementary to the groove *o*. The cover is placed over one end of the base die with its hinge wire above the groove *m* and resting on a support *r*, which is held in an upright guideway in the end of the base *k* and is supported by a spring *s*. Such support is beside the end of the groove *m* in the base die, and its function is to assist in supporting and locating the wired edge of the cover so that the U-shaped anchor strip will lie on its side and not be tipped up toward the punch member *l*. The support *r* also has a projection which rises within the cover close to that wall thereof to which the hinge wire is attached.

When the punch member *l* approaches the base member, it closes in the separated side of the U-shaped anchor piece, at the same time bending the sides down into the groove *o*, and closing them around the hinge wire, the support *r* then yielding to permit the wire being forced into the groove *m*. The ridge *n* then forms a bend in the tab at *t* near the eye of the hinge anchor, and another bend at *u*.

The hinge anchors thus closed and bent are passed through the slots in the ledge *b* of the base member, and the latter is placed, inverted, in another press, where the hinge wire is supported by an anvil *w* shown in Fig. 6. The folding die *x* of this press then descends upon the bent tabs and flattens them down into the shape shown in Figs. 2 and 3, already described.

The part of the tab between its extremity and the fold *u* is preferably made long enough to extend out to the adjacent parallel wall of the base member, when fully flattened down, in order that the end of the tab, when being thus folded down, may bear on said wall and be guided into the prescribed position, where the flanges will extend a sufficient distance to each side of the slot.

10 While this last feature is an advantage, it is not essential, and I may reverse the anchor tab in position, as shown in Fig. 3. The essentials of this form of anchor and the method of forming it are the same as already described, and the only difference is that the advantages due to having the end of the tab bear on the side of the base member are relinquished.

As a result of the preliminary bending of the tab, there is no possibility of any of the hinge anchors becoming so far tilted or cocked in the final folding press as to prevent the tabs being correctly formed and positioned, but all the tabs are folded alike. At 25 the same time, the preliminary bending leaves the angles in the tabs wide enough to permit of quick and easy insertion through the slots of the base member.

While I have described the invention in terms particularly applicable to the art of sheet metal cans or can rims and their covers, it is to be understood my protection is not limited to this art or class of goods, but includes the essential features of my improved hinge and the mode of making it, herein described and hereinafter pointed out in the claims, for use in any structure where the same may be applicable. In the generic sense, the base frame herein described typifies any member to which another member may be hinged, and the cover typifies any swinging member which may be connected to another structure by a hinge, while the hinge wire typifies a pintle of any sort.

What I claim and desire to secure by Letters Patent is:

1. A hinge comprising the combination between one member having a slotted wall and a second member, of a rod or wire adapted to serve as a hinge pintle, and a hinge anchor consisting of a strip of sheet metal bent near its middle to surround the said hinge pintle and to form a tab, said tab

passing through the slot of said slotted wall and being bent to lie against the surface at one side of the slot, folded at the same side of the slot, and extending from its fold across the slot.

2. In a hinge the combination between a member having a side wall and a ledge, said ledge containing a slot parallel to and spaced apart from said wall, of a hinge anchor consisting of a sheet metal strip bent double and formed with a hinge eye and a tab extending through said slot so that said eye is close to one surface of the slotted ledge, said tab being sharply bent and laid against the adjacent surface of the ledge at one side of the slot, then folded double and extended across the slot and adjacent to the same surface of the ledge at the opposite side of the slot.

3. In a hinge the combination between a member having a wall and an end ledge, said end ledge containing a slot parallel to and spaced apart from said wall, and a hinge anchor consisting of a sheet metal strip bent double to form a hinge eye and extending through said slot so that said eye is close to one surface of the slotted ledge, the part of the anchor at the other side of the ledge being sharply bent away from said wall and laid against the adjacent surface of the ledge then folded double and extending from the fold substantially to said wall and against the adjacent surface of the ledge.

4. The method of forming and applying a hinge anchor of the character described to a slotted member, which consists in folding a strip of sheet metal to provide a hinge eye, and a tab projecting from said eye, at the same time forming opposite angular bends in said tab at different distances from the eye, passing the tab thus bent through said slotted member until the hinge eye is near one surface of said member and the bend nearest to the eye is at the opposite side of the member, then pressing upon and further bending the bent tab toward the last named surface until the bent portions of the tab contact with each other and one of said portions bears against the adjacent surface of the slotted member.

In testimony whereof I have affixed my signature.

CHARLES H. CAMPBELL.

CERTIFICATE OF CORRECTION.

Patent No. 1,654,362.

Granted December 27, 1927, to

CHARLES H. CAMPBELL.

It is hereby certified that error appears in the printed specification of the above numbered patent requiring correction as follows: Page 2, line 113, for the misspelled word "separted" read "separated"; and that the said Letters Patent should be read with this correction therein that the same may conform to the record of the case in the Patent Office.

Signed and sealed this 31st day of January, A. D. 1928.

M. J. Moore,
Acting Commissioner of Patents.
